CLAIM

The ornamental design for an inline skate frame as shown and described.

DESCRIPTION

FIG. 1 is an upper perspective view of an embodiment of an inline skate frame showing my new design; FIG. 2 is a lower perspective view thereof; FIG. 3 is a left side elevation view thereof; FIG. 4 is a right side elevation view thereof; FIG. 5 is a top plan view thereof; FIG. 6 is a bottom plan view thereof; FIG. 7 is a front elevation view thereof; FIG. 8 is a back elevation view thereof; FIG. 9 is an upper perspective view of an alternate embodiment of an inline skate frame showing my new design; FIG. 10 is a lower perspective view thereof; FIG. 11 is a left side elevation view thereof; FIG. 12 is a right side elevation view thereof; FIG. 13 is a top plan view thereof; FIG. 14 is a bottom plan view thereof; FIG. 15 is a front elevation view thereof; and, FIG. 16 is a back elevation view thereof. FIGS. 1-8 above show a first embodiment. A third embodiment which is a symmetrical version of the first embodiment is also considered part of the claimed design. FIGS. 9-16 above show a second embodiment. A fourth embodiment which is a symmetrical version of the second embodiment is also considered part of the claimed design. The broken lines illustrate portions of the inline skate frame that form no part of the claimed design.
